UNITED STATES PATENT OFFICE

EUGENIA S. GORDON, OF NEW ROCHELLE, NEW YORK

WINDOW-CLEANING DEVICE

Application filed July 8, 1929. Serial No. 376,742.

My invention relates to a window cleaning device comprising a thin washing and a thin drying element, respectively carried at opposite ends of a slender, substantially rigid rod, 5 which permits the user to clean the inside and outside of the panes of each window frame while standing on the floor of the room.

One of the objects of my invention is to provide a slender, substantially rigid rod which 10 carries a thin washing and a thin drying element at opposite ends thereof, the parts being so constructed and arranged that the rod and the washing and the drying elements may pass between the outer and inner frames of 15 the window.

Another object of the invention is to provide such a device which, when assembled, consists of a single member, so that it may be used with one hand to first wash and later dry the windows, the rigidity of the rod carrying the washing and drying elements permitting sufficient pressure to be transmitted to the elements, when the device is between the window frames, to efficiently clean the inside of the panes of the outer frame and the outside of the panes of the inner frame.

Another object of the invention is to provide means pivotally secured to the rod, for securing the rod to the hand of the user, thus 20 permitting the rod to be reversed at will without danger of dropping the rod as from a window of considerable height above the ground.

Another object of the invention is to provide such a device consisting, when assembled, of a single member, which employs a minimum number of parts and which may be easily and economically manufactured.

With the above and other objects in view, 25 my invention consists in the parts, improvements and combinations more fully pointed out hereinafter.

Referring now to the drawings:

Figure 1, is a front elevation of the device showing the washing and the drying elements carried at opposite ends of the rod.

Figure 2, is a side detail view of the form shown in Figure 1, showing the drying element arranged substantially perpendicular to and projecting slightly beyond the rod.

Figure 3 is a side elevation of a modified form of the invention showing the washing element wrapped around one end of the rod and the drying element mounted lengthwise of and at the opposite end of the rod. 55

Figure 4, is a view through a window construction showing the device illustrated in Figures 1 and 2, when used to clean the outside of the panes of the lower, inner window sash. 60

In the preferred form shown in Figures 1, 2 and 4, the rod 1, is of slender and substantially rigid construction. Carried at one end of the rod is an open-ended wire loop 2, whose open ends 3, are soldered to the rod. The 65 loop 2, is adapted to hold a suitable thin washing element 4, such as cloth or the like, which may be wrapped around the loop. Carried at the opposite end of the rod is a metal member 5, adapted to hold the thin 70 drying element 6, which may be of rubber. Member 5, is soldered to the rod and is mounted substantially perpendicular thereto. This member projects slightly beyond the rod. Rod 1, also carries a sliding ring 7, which is 75 adapted to move freely along and to revolve about the rod. Ring 7, carries a swivel 8, to which is secured a wristband or handgrip 9.

In the modified form shown in Figure 3, the rod 1, is of similar construction to that 80 shown in Figure 1. In this form the washing element 4, may be wrapped about one end of the rod and suitably secured thereto, as by elastics. The other end of the rod carries a holding member 10, which is preferably of 85 triangular shape and adapted to carry the drying element, such as rubber strip 6. The holding member is soldered to the rod and extends lengthwise thereof. Similar means are provided for securing the rod to the wrist 90 or hand of the user.

The projection of the drying and washing elements from the rod, in both forms, is only slightly beyond the rod, and allows both elements with the rod to be inserted between 95 the frames 11 and 12 of the windows.

It will thus be seen that in both forms a simplified and improved form of window cleaning device has been provided, which consists of a single member. It may be 100

used with one hand to clean the window panes, inside and out of both sashes. It avoids the necessity for strapping or clamping the device to the window sill. It allows the user to efficiently clean the windows from the floor of the room, without standing on the sill, or a ladder. The device may, of course, be made in several standard sizes to be used with windows of various lengths.

10 In use the wristband or handgrip is slipped over the wrist or about the hand of the user and the rod grasped with one hand. The thin washing element having been suitably moistened may then be used to wash the
15 windows. The grip on the rod may then be released. The sliding ring and swivel permits the rod to be quickly reversed. The wristband or handgrip avoids the danger of the device falling from the window to the
20 ground. The thin drying element may then be used, after reversal of the rod, to dry the windows. When the outside panes of the lower, inner sash are to be cleaned, the portion of the rod at the end which carries the
25 washing element is inserted, with the washing element, between the window sashes, after the lower sash has been thrown up. The outside panes of the lower sash are then washed. The rod and washing element
30 are then withdrawn and the rod reversed. The drying element and the rod are then reinserted, as shown in Figure 4, and the panes thoroughly dried. As shown in this figure, the rod may be gripped so that sufficient pressure
35 is transmitted to the drying element to thoroughly dry the windows. It will also be noted that the construction and arrangement of the parts is such that the device may be manipulated without interference.
40 Having thus described the invention and its operation, it will be understood that changes may be made in carrying the invention into effect, without departing from the principle thereof.

45 What I claim is:

A window cleaner composed of a relatively slender and substantially rigid rod having window engaging means on its respective ends, a sleeve slideable and rotatable on the rod between the ends of the rod, a wrist encircling member, and means to swivelly connect said wrist encircling member to the sleeve, whereby the rod may be rotated about said wrist encircling member to reverse its ends, while the wrist encircling member remains on the wrist of the operator, thereby to enable first cleaning and then drying of the window.

In witness whereof, I have signed my name
60 to this specification.

EUGENIA S. GORDON.
